UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

DESIGN FOR A TALCUM-POWDER BOX.

59,096.

Specification for Design. Patented Sept. 20, 1921.

Application filed December 13, 1920. Serial No. 430,469. Term of patent 3½ years.

To all whom it may concern:

Be it known that I, JOHN M. HOTHERSALL, a citizen of the United States, residing at Brooklyn, county of Kings, and State of New York, have invented a new, original, and ornamental Design for a Talcum-Powder Box, of which the following is a specification, reference being had to the accompanying drawing, forming a part thereof.

On the drawing:

Figure 1 is a top plan view of a talcum

powder box embodying my present invention; and

Fig. 2 is a side elevation thereof.

I claim:

The ornamental design for a talcum powder box as shown.

JOHN M. HOTHERSALL.
